No. 13,396

Nov 7, 1882

UNITED STATES PATENT OFFICE.

GEORGE S. HENSEL, OF PHILADELPHIA, PENNSYLVANIA.

DESIGN FOR BALL-FRINGE.

SPECIFICATION forming part of Design No. 13,396, dated November 7, 1882.

Application filed October 4, 1882. Term of patent 7 years.

To all whom it may concern:

Be it known that I, GEORGE S. HENSEL, a citizen of the United States, residing in the city and county of Philadelphia, State of Pennsylvania, have invented and produced a new and original Design for Ball-Fringe, of which the following is a specification, reference being had to the accompanying photographic illustration, forming part thereof.

My design for a fringe consists of flat pendants, the faces whereof are ornamented by balls.

A represents pendants which, connected with

a suitable head, are of flat form. On the faces of the pendants are balls B, of which any number may be used, said balls being denominated by me as "plush balls," the whole forming a beautiful and attractive design. 15

I claim—

The design for fringe, having flat pendants 20 with balls thereon, substantially as above described and shown.

GEO. S. HENSEL.
